CAR ROOF

Charles David Bonsail, Pittsburgh, Pa., assignor
to P. H. Murphy Company, New Kensington,
Pa., a corporation of Pennsylvania

Application June 28, 1935, Serial No. 28,818

6 Claims. (Cl. 108—5.4)

This application is a continuation in part of my copending application for patent for Car roof, Serial No. 659,491, filed March 3, 1933. The invention consists in the arrangements and combinations hereinafter described and claimed.

5 In the accompanying drawing, which forms part of this specification, and wherein like symbols refer to like parts wherever they occur,

Fig. 1 is a plan view of a part of a car roof embodying my invention,

10 Fig. 2 is a sectional view crosswise of the car on the line 2—2 of Fig. 1,

Fig. 3 is a sectional view lengthwise of the car on the line 3—3 of Fig. 1, and

15 Figs. 4, 5, 6, 7, 8 and 9 are views similar to Fig. 3 illustrating modifications.

The construction illustrated in Figs. 1 to 3 comprises metal side plates 1, carlines 2 whose ends are secured to the side plates and roof sheets 20 which extend from side plate to side plate and from carline to carline. The ends of the roof sheets are preferably turned down and secured to the outer faces of the carlines by welds 3 of added metal that join the end edges of the 25 sheets to the outer faces of the side plates.

In the construction illustrated in Figs. 1 to 3, the carlines 2 are of channel shape with horizontal flanges 2a extending laterally from the tops thereof; and the roof sheets comprise a 30 series of plain wide roof sheets 4 that span from carline to carline and a series of plain narrow roof sheets 5 that alternate with the wide sheets and are located above the respective carlines. The wide sheets 4 lap the flanges 2a of the carlines 35 2 and the intervening narrow sheets 5 are somewhat narrower than the distance between successive wide sheets and are arranged with their edges spaced somewhat from the edges of the adjacent wide sheets. The spaces between the edges 40 of the adjacent sheets are filled with welds 6 of added metal which secure the edges of adjacent sheets together and also to the tops of the carline flanges.

The construction illustrated in Figs. 1 to 3 has 45 several advantages. It has all of the advantages that come from welding as compared with riveting and it makes use of plain sheets which do not need to be accurately sized as to width. For this reason, the invention is particularly applicable to the reconstruction of roofs of the type 50 wherein successive roof sheets meet or lap at the carlines. Roofs of this type usually fail by the tearing or rusting out of their edge portions while the main body of the sheet is still in sound condition. By shearing off the defective marginal

portions of such sheets, they are still left wide enough for use as the wide sheets of the construction above described. In the case of old sheets that are too badly torn for use as wide sheets, they can be sheared to produce one or more of the 5 narrow sheets of my construction.

Another advantage of the construction illustrated in Figs. 1 to 3 is that the narrow roof sheet cooperates with the channel carline to constitute a hollow box girder in which the narrow sheet functions as the top plate. As this top plate is a separate piece from the wide roof sheet, it may be made of whatever thickness the designing engineer may think advisable to meet the engineering requirements of the structure. In the 10 modification illustrated in Fig. 4, the narrow sheet or top plate 5a of the hollow box girder is considerably thicker than the wide roof sheets 4.

The construction illustrated in Fig. 5 is generally similar to the construction of Figs. 1 to 3 15 except that the modification illustrated in Fig. 5 uses the same flanges and channel-shaped carline as the construction of Fig. 3 and secures the edges of adjacent sheets 6 together and to the carline by welds 7 that fill the spaces between 20 adjacent sheets. In this modification, one of the sheets is wide enough to reach from one carline to the far flange of the next adjacent carline, where its end is secured to the carline and to the adjacent sheet. In this construction, adjacent 25 sheets may be of equal width or of unequal width. When they are of unequal width, a narrower sheet is wide enough to overlap the edges of adjacent carlines far enough for convenient welding. This arrangement of wide and narrow sheets is 30 particularly advantageous in that it makes it 35 possible to salvage wide sheets with torn edges by trimming off the torn portions.

The modification illustrated in Fig. 6 is similar to the construction of Fig. 5 except that the 40 sheets consist of two series alternating with each other. The sheets of one series are plain thick sheets 8, that rest on top of the carlines 2 and the sheets of the other series are thin sheets 9 whose body portions are at a lower level and which are 45 provided with upstanding angular flanges 9a whose edges overlap the margins of the adjacent carlines and are welded thereto and to the edges of the adjacent sheets by single welds 10.

In the modifications illustrated in Figs. 7, 8 and 50 9, the carlines 11 are of inverted U-shape. In the construction of Fig. 7, plain roof sheets 12 rest on the horizontal top portion of the carline with their edges spaced apart and the spaces filled with welds 13 that secure adjacent sheets to- 55

gether and to the carline. Aside from the usual advantages of welding over riveting, this arrangement makes it possible to use old sheets with torn edges by trimming off the torn portions and still 5 leaving sheets that are wide enough for the purpose. It is particularly noted that the location of the weld crosswise of the carline may be shifted to suit the sheets, whereas the requirements for riveting fix the location of the rivet line within 10 narrow limits. Besides, riveting requires one workman inside of the car as well as another workman outside of the car, whereas a single welder outside of the car will make a better joint.

In the modification illustrated in Fig. 8, the 15 sides of adjacent sheets 14 lap the flanges 11a at the bottom of the intervening carline 11 and are respectively welded by welds 15 to said flanges. The particular merit of this design is that it permits the use of narrow sheets and is, therefore, 20 well adapted for salvaging old sheets with torn edges by trimming off the torn portions.

The modification illustrated in Fig. 9 comprises 25 an inverted channel-shaped carline 11 with lateral flanges 11a and plain roof sheets 16 that extend underneath the carlines and have their meeting edges welded together as at 17, underneath the carlines. Additional welds 18 of added metal secure the edges of the carline flanges to the upper faces of the roof sheets. In this modification, the roof sheets cooperate with the carlines to form hollow box girders that increase 30 the stiffness and strength of the structure.

What I claim is:

1. A car roof construction comprising car side 35 plates and a unitary self-supporting roof secured thereto, said roof consisting of alternately wide and narrow roof sheets arranged side by side with narrow spaces intervening, channel-shaped members below and of greater width than the narrow 40 sheets and with lateral flanges extending beneath the margins of the wider sheets and welds filling such spaces and uniting the edges of adjacent wide and narrow sheets together and to said members.

45 2. A car roof construction comprising car side plates and a unitary self-supporting roof secured thereto, said roof consisting of alternately wide and narrow roof sheets arranged side by side with narrow spaces intervening, channel-shaped members below and of greater width than the narrow 50 sheets and with lateral flanges extending beneath the margins of the wider sheets and welds filling such spaces and uniting the edges of adjacent wide and narrow sheets together and to said members, the narrow sheets being thicker

than the wide sheets and cooperating with the channel-shaped members as the top chord of the hollow box beam.

3. A car roof comprising side plates, carlines secured thereto, roof sheets supported directly 5 and entirely by said side plates and carlines and whose ends are secured to the side plates and whose sides are secured to the carlines, said carlines comprising a body portion with lateral flanges, said roof sheets having flat horizontal 10 side margins which are spaced apart from each other and rest flatwise on top of the flanges of the carlines to which they are secured, and welds of added metal uniting said sheets to said flanges, said welds being opposite the edges of the sheets 15 and opposite the upper faces of the flanges of the carlines united thereby.

4. A car roof comprising side plates, carlines secured thereto, roof sheets whose ends are secured to the side plates and whose sides are secured to the carlines, said carlines comprising a hollow body portion with lateral flanges, said roof sheets being of less width than the distance between the body portions of adjacent carlines and having flat horizontal margins that rest on top 20 of the flanges of adjacent carlines, and continuous welds of added metal located above said flanges and uniting said sheets to said flanges, said welds being opposite the edges of the sheets and opposite the faces of the carlines united 30 thereby.

5. A car roof comprising side plates, carlines secured thereto, roof sheets whose ends are secured to said side plates and whose sides are secured to the carlines, said carlines comprising 35 a flat horizontal middle portion and vertically disposed sides with lateral flanges, said roof sheets being of less width than the distance between the sides of adjacent carlines and having flat margins that rest flatwise upon the flanges of 40 adjacent carlines, and continuous welds of added metal uniting the edges of the sheets to the tops of said flanges.

6. A car roof comprising side plates, carlines of inverted U-shape with flat tops and with outwardly extending flanges at the bottom thereof, roof sheets extending from side plate to side plate with their ends secured to said side plates and with flat horizontal side margins resting on top of the flanges of adjacent carlines and spaced 50 from the vertical side portions thereof and continuous welds of added metal uniting the edges of the sheets to said flanges whereby the carlines cover the spaces between adjacent sheets.
